UNITED STATES PATENT OFFICE.

PETER G. MACGREGOR, OF PEQUANNOCK, NEW JERSEY, ASSIGNOR TO PYRENE MANUFACTURING COMPANY, OF NEWARK, NEW JERSEY, A CORPORATION OF DELAWARE.

Thermal Valve.

Application filed February 13, 1922. Serial No. 536,357.

This invention relates to thermally-controlled releasing devices and is designed to release a desired part for operation upon the rise in temperature of the surrounding medium above a predetermined degree. More particularly, the device is a thermal valve which upon said rise in temperature opens a plurality of ports to permit liquid to flow therethrough. The invention is particularly adapted for use with automatic sprinkler systems to secure distribution of the fire-extinguishing fluid over any desired area, but it will be understood that the device is not limited to such use.

Other features and advantages will hereinafter appear.

In the accompanying drawings:

Fig. 1 is a front view, vertically sectioned, of the device forming the subject of my invention.

Fig. 2 is a plan view.

Referring to the drawings, there is shown an externally-threaded collar 9 fixed to a base-plate or wall 10. Upon the collar 9 is screwed a shell 11, and a chamber 12 is fixed upon the opposite side of the base-plate. In the upper end of shell 11 operates a valve comprising a substantially cylindrical valve-member 15 extending upwardly and slidably through openings in the shell 11, base-plate 10 and chamber 12 into said chamber. The latter is provided with openings in its side walls into which fit a corresponding number of conduits such as 17, 18. The chamber 12 is also provided with an opening in its top wall into which fits a plug 20 having an opening therethrough to permit passage of a supply conduit 19. It will be obvious that if conduit 19 is connected to a source of liquid, and said conduit is open, liquid will flow into chamber 12 and thence to distributing conduits 17, 18 to be distributed as desired. Means are therefore provided whereby the conduit 19 is normally closed but which is opened upon a predetermined rise in temperature of the surrounding medium.

For this purpose the end of conduit 19 is normally closed by the cone-shaped top 22 of the valve-member 15, said valve-member resting at its lower end upon a plate 23 and being held against the end of said conduit by a coil-spring 24 pressing against said plate. The spring is supported in position by a thermal release device comprising two members or levers 25 and 26, each of said levers

being supported at their upper ends 39 and 40 upon a flange 27 on the lower end of shell 11 and having their lower ends extending outwardly and downwardly and normally held against movement relative to each other by strips of metal 28 and 29 soldered together by low-fusing metal 30 and connecting the lower ends of said members. This construction permits a quick release, as the fusible metal is fully exposed. One of the levers 25, 26 (here shown as lever 25) is provided with a ridge 31 normally seated in a corresponding groove in the other lever (here shown as lever 26) so that a toggle-joint is formed.

In operation, when the temperature of the surrounding medium rises sufficiently to fuse the solder 30, the latter will yield, and spring 24 will swing levers 25 and 26 about ridge 31 as a pivot so that ends 39 and 40 swing towards each other and allow the levers 25 and 26, the spring 24 and plate 23 to drop out of shell 11. The tension of the spring being released, valve-member 15 will move away from the end of conduit 19 permitting the liquid to discharge into chamber 12 and thence into the distributing conduits. The movement of valve-member 15 away from the end of conduit 19 is limited by a flange 32 carried by member 15 and engaging the bottom wall 33 of the chamber 12. The valve-member may be provided above flange 32 with openings 34 so that liquid may discharge into the valve-member, which being hollow, acts as a conduit similar to conduits 17, 18. The liquid also discharges from the chamber 12 through a chamber-outlet opening 35, formed in the base 36 of the valve member 15, and is distributed through side openings 41 and a bottom opening 42 in the shell 11. Adjacent the base 36 may be supported a spirally-grooved member 37 whereby a whirling motion is given to the liquid.

The device has been illustrated as mounted upon a base 10 which may be the wall of a container. Any number of conduits may be led out from chamber 12 to distribute the liquid to any desired points. After operation, it is only necessary to unscrew shell 11 from collar 9 and substitute a new shell therefor having a plate 23, spring 24, and members 25 and 26 held by soldered strips 28 and 29. The device is then ready for another operation.

The above description illustrates a pre-

ferred form of my invention, but it will be understood that variations may be resorted to within the scope of the annexed claims.

Claims:—

- 5 1. A thermally-controlled liquid supply device comprising a liquid chamber, a distributing conduit and a supply conduit connected to said chamber, a valve comprising a hollow member extending into said chamber and having openings in its side and lower end walls and its upper end adapted to close said supply conduit, means normally holding said valve in effective position to close said supply conduit and valve member and prevent distribution of liquid in said distributing conduit, said means being held effective by a readily fusible body.
- 10 2. A thermally-controlled liquid supply device comprising a liquid chamber, a distributing conduit and a supply conduit connected to said chamber, a valve comprising a hollow member having openings in its side wall which permit the liquid to pass therethrough when said supply conduit is open and an end portion adapted to close said supply conduit, means normally holding said valve in effective position to close said supply conduit and prevent distribution of liquid in said distributing conduit, said means being held effective by a readily fusible body.
- 15 3. A thermally-controlled liquid supply device comprising a liquid chamber, a distributing conduit and a supply conduit connected to said chamber, a valve cooperating with said supply conduit, said chamber having an opening through which said valve passes, a shell removably fixed relative to said chamber and into which said valve extends, and means in said shell for normally pressing said valve into said chamber and holding the same in effective position to close said supply conduit and prevent distribution of liquid in said distributing conduit, said means being held effective by a readily fusible body attached thereto.
- 20 4. A thermally-controlled liquid supply device comprising a liquid chamber, a distributing conduit and a supply conduit connected to said chamber, a valve co-operating with said supply conduit, said chamber having an opening through which said valve passes, a shell removably fixed relative to said chamber and into which said valve extends, and means in said shell for normally pressing said valve into said chamber and holding the same in effective position to close said supply conduit and prevent distribution of liquid in said distributing conduit, said means being held effective by a readily fusible body attached thereto, said valve comprising a hollow member having openings which permit the liquid to pass therethrough and discharge into said shell when said body is fused and said valve moves to ineffective position to open said supply conduit, and a spirally-grooved member in said hollow valve member adjacent the discharge open-

ineffective position to open said supply conduit, said shell having openings which permit the liquid to be discharged therefrom.

5. A thermally-controlled liquid supply device comprising a liquid chamber, a distributing conduit and a supply conduit connected to said chamber, a valve cooperating with said supply conduit, said chamber having an opening through which said valve passes, a shell removably fixed relative to said chamber and into which said valve extends, means in said shell for normally pressing said valve into said chamber and holding the same in effective position to close said supply conduit and prevent distribution of liquid in said distributing conduit, said means being held effective by a readily fusible body attached thereto, said valve moving to ineffective position to open said supply conduit when said body is fused, and means carried by said valve for limiting its movement to ineffective position.

6. A thermally-controlled liquid supply device comprising a liquid chamber, a distributing conduit and a supply conduit connected to said chamber, a valve cooperating with said supply conduit, said chamber having an opening through which said valve passes, a shell removably fixed relative to said chamber and into which said valve extends, means in said shell for normally pressing said valve into said chamber and holding the same in effective position to close said supply conduit and prevent distribution of liquid in said distributing conduit, said means being held effective by a readily fusible body attached thereto, said valve moving to ineffective position to open said supply conduit when said body is fused, and means carried by said valve for limiting its movement to ineffective position, said means comprising a flange engageable with said chamber.

7. A thermally-controlled liquid supply device comprising a liquid chamber, a distributing conduit and a supply conduit connected to said chamber, a valve cooperating with said supply conduit, said chamber having an opening through which said valve passes, a shell removably fixed relative to said chamber and into which said valve extends, means in said shell for normally pressing said valve into said chamber and holding the same in effective position to close said supply conduit and prevent distribution of liquid in said distributing conduit, said means being held effective by a readily fusible body attached thereto, said valve comprising a hollow member having openings which permit the liquid to pass therethrough and discharge into said shell when said body is fused and said valve moves to ineffective position to open said supply conduit, and a spirally-grooved member in said hollow valve member adjacent the discharge open-

ing thereof, said shell having openings which permit the liquid to be discharged therefrom.

8. A thermally-controlled liquid supply device comprising a liquid chamber, a supply conduit and a plurality of distributing conduits connected to said chamber, a valve cooperating with said supply conduit, and means normally holding said valve in effective position to close said supply conduit and prevent distribution of liquid in said distributing conduits, said means being held effective by a readily fusible body, said valve moving to ineffective position to open said supply conduit and permit distribution of liquid to said distributing conduits when said body is fused.

9. A thermally-controlled liquid supply device comprising a liquid chamber, a supply conduit and a distributing conduit connected to said chamber, a valve provided with chamber outlet means and normally preventing communication of said supply conduit with said distributing conduit and outlet means, means for normally maintain-

ing said valve closed, and a thermal release device adapted upon being subjected to heat to release said valve whereby communication of said supply conduit with said distributor conduit and said outlet means is established.

10. A thermally-controlled liquid supply device comprising a liquid chamber, a distributing conduit and a supply conduit connected to said chamber, a valve normally preventing communication between said supply conduit and said distributing conduit, said valve comprising a hollow member communicating with said chamber and provided with an outlet opening, means for normally maintaining said valve closed, and a thermal release device adapted when subjected to heat to release said valve whereby communication of said supply conduit with said distributing conduit and said hollow member is established through said chamber.

Signed at New York in the county of New York and State of New York this 28th day of Jan., A. D. 1922.

PETER G. MACGREGOR.
